DESIGN FOR A COAT

Harry Goldberg, New York, N. Y., assignor to Morris W. Haft & Bros., Inc., New York, N. Y.

Application December 23, 1948, Serial No. 150,338

Term of patent 3½ years

(Cl. D3—4)

To all whom it may concern:

Be it known that I, Harry Goldberg, a citizen of the United States of America, residing in New York city, county of New York, and State of New York, have invented a new, original, and ornamental Design for a Coat, of which the following is a specification, reference being had to the accompanying drawing, forming part thereof, wherein,

I claim:

The ornamental design for a coat, substantially as shown.

HARRY GOLDBERG.
